(57) CLAIM

The ornamental design for a shoe as shown and described.

DESCRIPTION

FIG. 1 is a front perspective view of a shoe showing my new design;

FIG. 2 is a side view thereof; and,

FIG. 3 is a rear perspective view thereof.

The racetrack shaped broken line region within the shaded area forms no part of the claimed design. The parallel broken lines and the unshaded region therebetween adjacent to the top of the shaded area form no part of the claimed design. The broken lines depicting the remainder of the shoe form no part of the claimed design.
